LINER HANGER APPARATUS

William D. Myers, Houston, Tex., assignor to Baker Oil Tools, Inc., Los Angeles, Calif., a corporation of California

Filed Jan. 12, 1962, Ser. No. 165,857
16 Claims. (Cl. 166—203)

The present invention relates to subsurface well bore apparatus, and more particularly to apparatus for running a liner in a well bore and securing it therewithin.

An object of the present invention is to provide an improved liner hanger apparatus capable of being readily run in a well bore, set in place, the setting tool portion of the apparatus being easily released from the remainder of the apparatus for withdrawal from the well bore.

Another object of the invention is to provide a liner hanger apparatus adapted to be run in a well bore on a tubular string, which requires substantially no mechanical manipulation to effect its setting in the well bore, and having a setting tool readily released from the remainder of the apparatus to enable the tubular string and setting tool to be withdrawn from the well bore.

A further object of the invention is to provide a liner hanger apparatus which can be rotated, or reciprocated, or both, to correspondingly move a liner connected thereto and wall scratchers, or the like, mounted on the liner, without inadvertently setting the liner hanger in a cased well bore.

An additional object of the invention is to provide a liner hanger apparatus adapted to be set hydraulically in a cased well bore as an incident of depositing cementitious material behind the liner suspended from the liner hanger portion of the apparatus.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

FIGURE 1 is a longitudinal section through a liner hanger apparatus and a liner suspended therefrom, with the parts in condition for lowering the apparatus on a tubing string in a well casing;

FIG. 2 is a longitudinal section, on an enlarged scale, through an upper portion of the liner hanger apparatus disclosed in FIG. 1;

FIG. 3 is a view similar to FIG. 1 disclosed the liner hanger partially set in the well casing;

FIG. 4 is an enlarged longitudinal section of the liner hanger portion of the apparatus illustrated in FIG. 3;

FIG. 5 is a longitudinal section similar to FIGS. 2 and 4, showing the liner hanger anchored in packed-off condition in the well casing;

FIG. 6 is a cross-section taken along the line 6—6 on FIG. 2;

FIG. 7 is an enlarged fragmentary longitudinal section through the portion of the apparatus connecting the setting tool to the liner hanger, prior to release of the setting tool from the liner hanger.

As shown in the drawings, a liner A is connected to the lower end of a liner hanger B releasably secured to a setting tool C connected to a tubular string D, such as tubing or drill pipe, extending to the top of a well bore E containing a well casing F. Usually the liner A is to be set in the lower portion of the well casing F, with the liner in overlapping relation therewith, but extending to the

2

desired extent in the well bore below the lower end of the well casing.

The liner A is of a suitable length and diameter, terminating in a lower shoe G having a cement plug 10 therein which has a central passage 11. Circulating fluid, cementitious material, and other fluent substances can be pumped down through the liner A and through the central passage 11 in the shoe for discharge into the well bore E. However, reverse flow of such fluid can be prevented, 10 as by the upward movement of a back pressure valve element 12 into engagement with a companion valve seat 13 appropriately secured within the cement plug 10 of the shoe.

The upper end of the liner A is threadedly secured to 15 the lower end of the tubular body portion 14 of the liner hanger B, this tubular body portion having an upper head or abutment 15 threaded on its upper end. Surrounding the body and with its upper portion in engagement with the upper abutment 15 is a suitable packing structure 16, 20 such as a pliant, elastic packing sleeve of rubber or rubber-like material, the lower end of which engages an expander 17 having an external surface 18 tapering in a downward and inward direction. This expander engages companion internal tapered surfaces 19 on a plurality of 25 segmental slips 20 initially retained in retracted position in any suitable manner, as by having shear screws 21 attaching them to the lower portion of the expander 17. The slips have external wickers or teeth 22 adapted to be embedded in the wall of the well casing to prevent downward movement of the liner hanger B therewithin.

Below the lower end of the slips 20 is an annular setting sleeve or cylinder 23, including a cylinder head 24 slidably on the body 14 and engageable with the slips 20. Depending from the head 24 is a cylinder skirt 25 slidable 35 along the lower piston portion 26 of the body 14, there being a cylindrical space 27 between the skirt 25 and the smaller diameter portion 28 of the body above its piston portion 26 into which fluid under pressure can be directed, and described hereinbelow. Leakage of fluid from the cylinder space 27 in an upward direction is prevented by a suitable side seal 29, such as a rubber or rubber-like O ring, disposed in an internal groove 30 in the cylinder head 24 and slidably sealing against the periphery of the body 14. Leakage of fluid in a downward direction from 40 the annular cylinder space 27 is prevented by a suitable side seal ring 31, such as a rubber or rubber-like O ring, disposed in an external groove 32 in the piston portion 26 of the body, and slidably sealing against the inner wall of the cylinder skirt 25.

50 The cylinder 23 can move upwardly relative to the body 14 when adequate fluid pressure is imposed on the liquid in the annular cylinder 27. However, downward movement along the body is prevented by a one-way lock device of any suitable type. As shown, the lock device may include a split lock ring or sleeve 33 disposed in an internal groove 34 in the cylinder head 24 and having an external surface 35 tapering in an upward and inward direction adapted to be engaged by a companion internal surface 36 in the groove. The ring 33 can move relatively 55 downwardly in the groove 34 to a released position, allowing the cylinder 23 to move upwardly along the body 14. However, any tendency for the cylinder or setting sleeve 23 to move downwardly causes the tapered surfaces 35, 36 to coengage and wedge the split lock ring 33 60 inwardly to embed its teeth 37 in the periphery of the body 14, the teeth facing in a downward direction, to prevent downward slipping of the ring 33 along the periphery of the body.

65 The liner hanger B and liner A are lowered by means of the tubular string D in the well casing F until the liner hanger is at the desired setting location in the well casing. The tubing string F is releasably connected to the

liner hanger B through the agency of the setting tool C. As shown, the lower end of the tubular string D is threadedly connected to a mandrel sub 38, which, in turn, is threadedly secured to the upper portion of a tubular mandrel 39 extending downwardly through the packer body 14. The mandrel 39 has an enlarged head 40 provided with circumferentially spaced longitudinally extending grooves 41 in which lock keys or dogs 42 are receivable. The lower ends 43 of the keys are inclined in a downward and outward direction, engaging companion lower ends 44 of the longitudinal grooves 41 which are inclined in the same direction. The upper ends 45 of the keys 42 engage a mandrel ring 46 threaded on the mandrel and having its lower end 47 tapered downwardly and inwardly. The ring carries a seal ring 48, of rubber or rubber-like material, in a groove 49, the seal having a downwardly facing lip 50 engaging the inner wall of the liner hanger body 14.

Each key 42 extends into a companion longitudinal slot 51 in the body 14, their outer ends 52 initially engaging the inner surface or wall 53 of the cylinder head 24, so that the keys do not interfere with the ability of the cylinder 23 to be hydraulically shifted upwardly along the body 14. When engaged with the inner wall 53 of the cylinder head, the keys 42 are retained within the longitudinal mandrel grooves 41, and thereby couple the setting mandrel 39 to the body 14 of the hanger B for longitudinal movement therewith in both directions, and also for rotary movement therewith. When the cylinder 23 is shifted upwardly along the body 14, for the purpose of setting the slips 20 against the well casing F, as described hereinbelow, the cylinder head 24 moves upwardly out of engagement with the lock keys or dogs 42, the larger internal diameter cylinder skirt portion 25 then being disposed opposite the keys, allowing the keys 42 to shift laterally outwardly into the annular cylinder space 27 and completely from the longitudinal grooves 41 in the mandrel 39, thereby freeing the mandrel from the body 14 of the liner hanger B. Such outward movement of the keys or dogs 42 may be assisted by upward movement of the mandrel 39 within the body 14, the lower tapered mandrel surfaces 44 urging the keys outwardly, or by downward movement of the mandrel 39 relative to the body 14, the upper tapered surface 47, 45 also urging the keys 42 in an outward direction. Initially, however, the keys 42 are retained in the body slots 51 and in the mandrel grooves 41 by the cylinder head 24, the sleeve 23 being prevented from inadvertently shifting upwardly along the body 14 by one or more shear screws 55 securing its skirt portion 25 to the lower portion of the liner hanger body 14.

Fluid pressure is availed of in the liner A to enter the annular cylinder space 27 through the body slots 51 for the purpose of disrupting the shear screws 55 and shifting the cylinder 23 upwardly along the body 14 to expand the slips 20 against the well casing F. Thus, the body slots 51 not only function to receive the keys or dogs 42 and couple the setting tool mandrel 39 to the body 14 of the liner hanger, but also as ports through which fluid can pass into the annular cylinder 27.

The liner, liner hanger and setting tool apparatus A, B, C are lowered in the well casing F by means of the tubular string D attached to the mandrel sub 38, the packing structure 16 and slips 20 being in their retracted position, and the keys 42 being held in a position coupling the setting tool mandrel 39 to the body 14 of the liner hanger by the setting sleeve head 24. The apparatus is run in the well casing until the liner hanger B is disposed in the lower portion of the casing at the desired setting point, with the liner A disposed partially in overlapping relation to the casing F, and also depending in the well bore E therebelow. Circulating fluid can then be pumped down through the tubular string D to the setting tool C, discharging into the liner A, which is of substantially greater internal diameter than the diameter

of the central passage 56 through the setting tool mandrel 39, and continuing through the shoe passage 11 into the well bore E, then passing upwardly through the annulus 57 between the liner A and the wall of the well bore E, as well as between the liner and liner hanger and the well casing, back through the tubing string-casing annulus 58 to the top of the well bore. During such circulation of fluid, the liner hanger B and liner A can be rotated, if desired, by rotating the tubular string D and the mandrel 38, 39, the rotary motion being transmitted from the mandrel through the keys 42 to the body 14 of the liner hanger B. The liner A may also be reciprocated in the well bore E to the desired extent, as by reciprocating the tubular string D and the mandrel 38, 39 connected thereto, the reciprocating movement being transmitted through the keys 42 to the body 14 of the liner hanger. Such rotary motion or reciprocating motion, or both, is desirable, as, for example, when rotary or reciprocating types of wall scratchers (not shown), or the like, are mounted on the liner A for the purpose of scratching the mud cake from the wall of the well bore E, to insure a proper cement bond between the cementitious material to be pumped into the well bore and the wall of the formation. The material scratched from the wall of the well bore is circulated out of the hole by the circulating fluid.

After the hole has been properly conditioned, it is desired to cement the liner A in place. A suitable charge of cement slurry or other cementitious material is pumped into the tubular string D, and on top of such charge of cement slurry is placed a top cementing plug H, followed by suitable displacement fluid. The top cementing plug may include a central rigid body 60 carrying a tubing seal or packing 61 adapted to slidably seal against the wall of the tubular string D and of the mandrel 39. Clamped to the body 60, as by means of a clamp nut 62, is an upwardly opening packing 63 adapted to expand outwardly sufficiently to slidably seal against the wall of the liner A, following discharge of the plug H from the setting tool mandrel 39. Such packing may have reinforcing leaf springs 64 on its exterior adapted to expand outwardly, and within such leaf springs, the packing 63 may be folded to some extent, as an umbrella is partially folded, the packing material being made of rubber or rubber-like material, or canvas reinforced with rubber.

The cement slurry is pumped down through the tubing string D ahead of the top cementing plug H, discharging from the mandrel 39 into the liner A and being adapted to pass downwardly through the central passage 11 of the liner shoe G into the well bore E, the cement slurry then passing upwardly around the liner A toward the liner hanger B. The liner hanger is then in an unset condition, so that the fluid ahead of the upwardly moving cement can pass upwardly through the clearing space between the liner hanger B and the well casing F. When the top cement plug H discharges from the lower end of the mandrel 39, its upper packing portion 63 will expand outwardly into sealing engagement with the inner wall of the liner A, the displacement fluid thereabove then acting on the packing element to hold it against the wall of the liner and forcing it downwardly in slidable sealing engagement with the latter to force the cement slurry ahead of it, until substantially all of the cement slurry is forced out of the liner, as determined by engagement of the plug body 60 with the plug 10 in the liner shoe G.

During the time that the cement slurry is being pumped into the liner A and then out of the liner, the tubular string D maintains the liner shoe off the bottom of the hole, or suspended from the liner hanger B. When the plug H bumps against the shoe G, pressure can then be built up in the displacement fluid above the plug, such fluid pressure passing between the lower portion of the mandrel 39 and the liner A, as well as between the mandrel and the liner hanger body 14, and through the ports 51 into the

annular cylinder 27. The fluid pressure cannot move above the location of the keys 42 because of the sealing action of the side seal 48 mounted on the mandrel ring 46 against the inner wall of the body 14 of the liner hanger. The fluid pressure in the annular cylinder 27 acts upwardly over the annular area of the cylinder head 24 between the periphery of the body 28 and the inner wall of the cylinder skirt 25. When it reaches a predetermined value sufficient to overcome the shear strength of the shear screws 55, the latter are disrupted and the cylinder 23 is then moved upwardly along the body 14. During the initial phase of such upward movement, the cylinder bears against the slips 20 to disrupt the shear screws 21 holding them in retracted position against the expander 17, moving the slips upwardly along the latter and laterally outwardly into engagement with the wall of the well casing F. If sufficient pressure is built up within the liner A and in the annular cylinder 23, it will slide the slips 20 upwardly along the wall of the casing F, carrying the expander 17 upwardly with it to at least partially shorten the packing 16 and expand it outwardly against the wall of the well casing.

The cylinder 23 moves upwardly sufficiently along the body 14 to expand the slips 20 against the well casing F and to place the enlarged internal diameter skirt portion 25 of the cylinder opposite the keys or dogs 42, which can then expand outwardly into the annular cylinder to remove their inner portions completely from the longitudinal grooves 41 in the mandrel 39, thereby freeing the mandrel 39 from the body 14 of the tool. The slip wickers 22 will embed themselves in the wall of the well casing to preclude downward movement of the slips 20 and of the expander 17 wedged behind them. To insure complete sealing off of the packing 16 against the wall of the well casing, the tubular string D and mandrel 38, 39 can then be lowered sufficiently, as permitted by the outward expansion of the locking dogs 42, to bring the lower shoulder 70 of the mandrel sub 38 into engagement with the upper end 71 of the upper body head or abutment 15. Sufficient downward weight can now be imposed upon the tubular string D and mandrel sub 38, which acts on the upper abutment 15 to shift the latter and the body connected thereto downwardly toward the stationary expander 17, to further shortening the packing 16 and compressing it fully and firmly into sealing engagement with the wall of the well casing F, and also inwardly against the periphery of the liner hanger body 14. Such downward imposition of force might not be necessary, since, following release of the lock dogs 42 from the mandrel 39, the weight of the liner A acting on the liner hanger body 14 and the upper abutment 15 might be sufficient to shift the upper abutment 15 toward the expander 17 and fully pack off the packing 16 against and between the body 14 and wall of the well casing F. Following full anchoring in packed-off condition of the liner hanger B against the casing F, its release is precluded by virtue of the fact that the setting sleeve or cylinder 23 cannot shift relatively downwardly of the body 14 because of the wedging of the lock ring 33 between the tapered surface 36 of the setting sleeve head 24 and the periphery of the body 14.

After the liner hanger B has been anchored in packed-off condition in the well casing, the tubular string D can be elevated to elevate the mandrel 38, 39 from the liner hanger. The tubular string and mandrel can then be thoroughly cleaned, and any excess cement that may have been deposited in the casing F above the liner hanger B removed from the well casing, as by pumping circulating fluid either downwardly through the tubular string D and out of the mandrel 39 for upward passage through the tubing-casing annulus 58 to the top of the hole, or by reversely circulating the cleaning fluid downwardly through the tubing-casing annulus 58 and then upwardly through the mandrel 39 and tubular string D to the top of the well bore. Back flow of cement slurry into the liner A is

prevented by upward seating of the ball valve element 12 against its companion seat 13 in the liner shoe G.

I claim:

1. In liner hanger apparatus adapted to be set in a well casing disposed in a well bore: a body; normally retracted means on said body adapted to be expanded outwardly against the well casing; hydraulically operable means on said body for expanding said normally retracted means; a setting tool; means releasably connecting said setting tool to said body; means retaining said releasable means in position connecting said setting tool to said body; and means responsive to movement of said hydraulically operable means in expanding said normally retracted means for shifting said retaining means to a position enabling said releasable means to be released and said setting tool disconnected from said body.
2. In liner hanger apparatus adapted to be set in a well casing disposed in a well bore: a body; normally retracted means on said body adapted to be expanded outwardly against the well casing; means on said body for expanding said normally retracted means; a setting tool; means releasably connecting said setting tool to said body; means retaining said releasable means in position connecting said setting tool to said body; and means responsive to movement of said expanding means in expanding said normally retracted means for shifting said retaining means to a position enabling said releasable means to be released and said setting tool disconnected from said body.
3. In liner hanger apparatus adapted to be set in a well casing disposed in a well bore: a body; normally retracted means on said body adapted to be expanded outwardly against the well casing; hydraulically operable means on said body for expanding said normally retracted means; a setting tool; means releasably connecting said setting tool to said body; said hydraulically operable means initially engaging said releasable means to retain said setting tool connected to said body and said hydraulically operable means being movable to expand said normally retracted means and to effect release of said releasable means to disconnect said setting tool from said body.
4. In liner hanger apparatus adapted to be set in a well casing disposed in a well bore: a body; normally retracted means on said body adapted to be expanded outwardly against the well casing; hydraulically operable means on said body for expanding said normally retracted means; a setting tool; means releasably connecting said setting tool to said body; said hydraulically operable means occupying an initial position engaging said releasable means and holding said releasable means coupled to said setting tool, said hydraulically operable means being shiftable, when expanding said normally retracted means, to another position allowing release of said releasable means from said setting tool to disconnect said setting tool from said body.
5. In liner hanger apparatus adapted to be set in a well casing disposed in a well bore: a body; normally retracted means on said body adapted to be expanded outwardly against the well casing; means on said body for expanding said normally retracted means; a setting tool; means releasably connecting said setting tool to said body; said expanding means initially engaging said releasable means to retain said setting tool connected to said body and said expanding means being movable to expand said normally retracted means and to effect release of said releasable means to disconnect said setting tool from said body.
6. In liner hanger apparatus adapted to be set in a well casing disposed in a well bore: a body; normally retracted means on said body adapted to be expanded outwardly against the well casing; means on said body for expanding said normally retracted means; a setting tool; means releasably connecting said setting tool to said body; said expanding means occupying an initial position engaging said releasable means and holding said releasable means coupled to said setting tool, said expanding means being shiftable, when expanding said normally retracted means,

to another position allowing release of said releasable means from said setting tool to disconnect said setting tool from said body.

7. In liner hanger apparatus adapted to be set in a well casing disposed in a well bore: a body member; normally retracted means on said body member adapted to be expanded outwardly against the well casing; hydraulically operable means on said body member for expanding said normally retracted means; a setting tool member; lock dogs coupled to said setting tool member and body member to releasably connect said setting tool member to said body member; means retaining said lock dogs in position connecting said setting tool member to said body member; and means responsive to movement of said hydraulically operable means in expanding said normally retracted means for shifting said retaining means to a position enabling said dogs to be uncoupled from one of said members to disconnect said members from each other.

8. In liner hanger apparatus adapted to be set in a well casing disposed in a well bore: a body member; normally retracted means on said body member adapted to be expanded outwardly against the well casing; means on said body member for expanding said normally retracted means; a setting tool member; lock dogs coupled to said setting tool member and body member to releasably connect said setting tool member to said body member; means retaining said lock dogs in position connecting said setting tool member to said body member; and means responsive to movement of said expanding means in expanding said normally retracted means for shifting said retaining means to a position enabling said dogs to be uncoupled from one of said members to disconnect said members from each other.

9. In liner hanger apparatus adapted to be set in a well casing disposed in a well bore: a body member; normally retracted means on said body member adapted to be expanded outwardly against the well casing; hydraulically operable means on said body member for expanding said normally retracted means; a setting tool member; lock dogs coupled to said setting tool member and body member to releasably connect said setting tool member to said body member; said hydraulically operable means occupying an initial position engaging and holding said dogs coupled to said setting tool member, said hydraulically operable means being shiftable, when expanding said normally retracted means, to another position allowing lateral outward movement of said dogs and their uncoupling from said setting tool member to release said setting tool member from said body member.

10. In liner hanger apparatus adapted to be set in a well casing disposed in a well bore: a body member; normally retracted means on said body member adapted to be expanded outwardly against the well casing; means on said body member for expanding said normally retracted means; a setting tool member; lock dogs coupled to said setting tool member and body member to releasably connect said setting tool member to said body member; said expanding means occupying an initial position engaging and holding said dogs coupled to said setting tool member, said expanding means being shiftable, when expanding said normally retracted means, to another position allowing lateral outward movement of said dogs and their uncoupling from said setting tool member to release said setting tool member from said body member.

11. In liner hanger apparatus adapted to be set in a well casing disposed in a well bore: a body; normally retracted means on said body adapted to be expanded outwardly against the well casing; a hydraulically operable sleeve on said body for expanding said normally retracted means; said body having a port for feeding fluid within said body to said sleeve to actuate the same; a setting tool in sealing relation to said body above said port; releasable means coupling said setting tool to said body; said sleeve initially engaging said releasable means to maintain said releasable means in coupling position; said sleeve

being shiftable on said body in response to fluid pressure in said body passing through said port to expand said normally retracted means and movable to a position releasing said releasable means from said setting tool to disconnect said setting tool from said body.

12. In liner hanger apparatus adapted to be set in a well casing disposed in a well bore: a body; normally retracted means on said body adapted to be expanded outwardly against the well casing; a hydraulically operable sleeve on said body for expanding said normally retracted means; said body having a port for feeding fluid within said body to said sleeve to actuate the same; a setting tool in sealing relation to said body above said port; lock dogs coupled to said setting tool and body to releasably connect said setting tool to said body; said sleeve occupying an initial position engaging and holding said dogs coupled to said setting tool member, said sleeve being shiftable on said body in response to fluid pressure in said body passing through said port to expand said normally retracted means and movable to a position allowing lateral outward movement of said dogs and their uncoupling from said setting tool to release said setting tool from said body.

13. In combination: a liner to be set in a well bore containing a well casing; a liner hanger including a body connected to the upper portion of said liner, normally retracted means on said body adapted to be expanded outwardly against the well casing, hydraulically operable means on said body for expanding said normally retracted means, said body having a port for feeding fluid under pressure within said body to said hydraulically operable means to actuate the same; a tubular setting tool in sealing relation to said body above said port and adapted to be connected to a tubular running-in string; means releasably connecting said setting tool to said body; said hydraulically operable means initially engaging said releasable means to retain said setting tool connected to said body; and means preventing discharge of fluid from said liner to enable fluid pressure to be imposed through the running-in string, setting tool, body and port to said hydraulically operable means to shift said hydraulically operable means on said body to a position expanding said normally retracted means and releasing said releasable means to disconnect said setting tool from said body.

14. In combination: a liner to be set in a well bore containing a well casing; a liner hanger including a body connected to the upper portion of said liner, normally retracted means on said body adapted to be expanded outwardly against the well casing, hydraulically operable means on said body for expanding said normally retracted means, said body having a port for feeding fluid under pressure within said body to said hydraulically operable means to actuate the same; a tubular setting tool in sealing relation to said body above said port and adapted to be connected to a tubular running-in string; means releasably connecting said setting tool to said body; said hydraulically operable means initially engaging said releasable means to retain said setting tool connected to said body; and a cementing plug adapted to be pumped through the running-in string, setting tool, body and port to said hydraulically operable means to shift said hydraulically operable means on said body to a position expanding said normally retracted means and releasing said releasable means to disconnect said setting tool from said body.

15. In combination: a liner to be set in a well bore containing a well casing; a liner hanger including a body connected to the upper portion of said liner, normally retracted means on said body adapted to be expanded outwardly against the well casing, hydraulically operable means on said body for expanding said normally retracted means, said body having a port for feeding fluid under pressure within said body to said hydraulically operable

means to actuate the same; a setting tool in sealing relation to said body above said port and adapted to be connected to a tubular running-in string; lock dogs coupled to said setting tool and body to releasably connect said setting tool to said body; said hydraulically operable means occupying an initial position engaging and holding said dogs coupled to said setting tool member; and means preventing discharge of fluid from said liner to enable fluid pressure to be imposed through the running-in string, setting tool, body and port to said hydraulically operable means to shift said hydraulically operable means on said body from said initial position toward a position expanding said normally retracted means and allowing lateral outward movement of said dogs and their uncoupling from said setting tool to release said setting tool from said body.

16. In combination: a liner to be set in a well bore containing a well casing; a liner hanger including a body connected to the upper portion of said liner, normally retracted means on said body adapted to be expanded outwardly against the well casing, hydraulically operable means on said body for expanding said normally retracted means, said body having a port for feeding fluid under

pressure within said body to said hydraulically operable means to actuate the same; a setting tool in sealing relation to said body above said port and adapted to be connected to a tubular running-in string; lock dogs coupled to said setting tool and body to releasably connect said setting tool to said body; said hydraulically operable means occupying an initial position engaging and holding said dogs coupled to said setting tool member; and a cementing plug adapted to be pumped through the running-in string, setting tool, and into said liner for preventing discharge of fluid from said liner to enable fluid pressure to be imposed through the running-in string, setting tool, body and port to said hydraulically operable means to shift said hydraulically operable means on said body to another position expanding said normally retracted means and allowing lateral outward movement of said dogs and their uncoupling from said setting tool to release said setting tool from said body.
